UNITED STATES PATENT OFFICE.

WALTER DE VILLE, OF EAST LIVERPOOL, OHIO, ASSIGNOR TO PALM, FECHTELER & CO.,
OF NEW YORK, N. Y., A CORPORATION OF NEW YORK.

DESIGN FOR A PLATE OR SIMILAR ARTICLE.

Application filed May 13, 1924. Serial No. 9,577. Term of patent 7 years.

To all whom it may concern:

Be it known that I, WALTER DE VILLE, a citizen of the United States, residing in East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article, as shown.

WALTER DE VILLE.

Witnesses:

HEBERT A. SMITH,
MARIE T. FAULK.
